Inventor:

Herbert C. Coy.

By Burton Burton his Atty.

Patented Oct. 27, 1925.

UNITED STATES PATENT OFFICE.

HERBERT C. COY, OF CHICAGO, ILLINOIS.

MAIL BOX.

Application filed March 16, 1922. Serial No. 544,112.

To all whom it may concern:

Be it known that I, HERBERT C. COY, a citizen of the United States, residing in the city of Chicago, in the county of Cook and the State of Illinois, have invented certain new and useful Improvements in Mail Boxes, of which the following is a specification, reference being had to the accompanying drawings, forming a part thereof.

10 The purpose of this invention is to provide an improved form and construction of a mail receiving box adapted for convenient withdrawal of mail matter deposited therein and for automatically signalling the deposit of mail by the carrier, and having other conveniences. It consists in the elements and features of construction shown and described as indicated in the claims.

In the drawings:—

20 Figure 1 is a perspective view of a mail box embodying this invention, showing the door through which the mail is to be withdrawn standing open.

Figure 2 is a perspective view of a supplementary detachable fixture containing auxiliary elements, as a speaking tube and a signalling connection comprising a push button.

Figure 3 is an interior perspective view of 30 a modified form of this supplementary fixture without the speaking tube connection.

Figure 4 is front elevation of the mail box, parts being broken away to show interior features.

35 Figure 5 is a partly sectional side elevation of the mail box for showing an exteriorly applied paper-holding arm, section being made in vertical fore-and-aft plane through the upper part of the box including the supplementary fixture at the top.

40 Figure 6 is a section at the line, 6—6, on Figure 5.

Referring to the drawings, the numeral 1, designates an oblong-shaped receptacle constituting the mail box, the interior chamber thereof being designated by the numeral 2. 45 3 is the door in the front of the receptacle mounted by interiorly positioned hinges, 4, for closing and unclosing the aperture, 5, in the front wall, 6, of the receptacle. 7 represents any convenient or suitable form of lock for securing the door closed. In the front wall, 6, of the receptacle there is provided a mail-receiving slot, 8, above the door and a little below the upper end of the receptacle. Secured to the inner face of the

door, 3, by riveting or other suitable means, there is an inwardly and upwardly extending mail-receiving ledge, 10, which might be described as a false bottom for the receptacle chamber, and which terminates extending upwardly, as seen at 11, the upper edge being designedly in contact with the back wall of the receptacle when the door is closed, so that all mail matter dropped through the slot will with certainty be lodged upon the ledge in front of its upwardly extending rear part, 11. The purpose of this is that when the door, 4, is opened, the entire mail matter which has been deposited will be carried out with the door upon the ledge and easily accessible for removal. To prevent letters which are entered through the slot of becoming engaged behind the margin of the front wall at the vertical edge of the door opening 75 opposite the hinged side of the door, which would create liability of mutilation by the upwardly extending rear part, 11, of the ledge in the opening of the door, there is provided an inclined plate, 13, secured to the side wall of the receptacle, extending inwardly overhanging the ledge, 10, and serving to deflect any mail matter which falls at that side, inwardly onto the ledge and past the edge of the door opening. It may be 85 understood that the door laps upon the margin of the door opening and is stopped thereby in the closing movement, as well as by the encounter of the rear upper edge of the part, 11, with the back wall. At 15 are 90 shown apertures at the lower part of the door through which the interior may be inspected to ascertain whether there is mail therein.

Fastened to one side of the receptacle, 1, 95 by a screw, 16, is a U-shaped bracket, 17, in which there is pivotally mounted an upwardly-extending rod, 18, held in engagement with the receptacle, 1, by means of a spring, 19, and constituting means for holding newspapers, magazines and the like, which are 100 too bulky for convenient insertion through the mail slot.

The receptacle is designed to be secured to a wall, and for that purpose screw apertures, 105 22, are shown in the back, 14.

The drawings show mounted upon the top of the receptacle, 1, a removable fixture somewhat of the nature of a casing, 26, which is secured to the receptacle by headed bolts or screws, 27, engaged non-rotatably with the bottom of the casing, 26, as

by a square shoulder, 27^a, adjacent the head, and thereby utilize the switch and wiring 60 entering corresponding parallel-sided slots, 28, which are enlarged at one end at 28^a, for admitting the heads of the bolts, said bolts 5 being secured by nuts, 27^b, applied inside the receptacle, 1, and thereby inaccessible for releasing the bolts and removing the fixture, 26, except upon unlocking and opening the door, 4, of the receptacle. Additional securing screws, 28^c, similarly engaged and mounted non-rotatably in the bottom of the case and secured by nuts within the receptacle are desirably employed to secure the fixture, 26, after it has been slid into place 10 along the length of the slots, 28. The fixture or casing, 26, is designed for accommodating a signal connection or connections and operating means for giving a signal when mail is deposited in the receptacle. For this purpose in-leading wires, 29, 29, of signal operating electric circuits are connected to contact springs, 31 and 32, secured to the top wall of the receptacle and terminating normally out of contact with each other, one overhanging the other as seen at 33; and 15 ing normally when the flap is closed, proximate to and it may be in contact, with the lower one of the spring contacts, 31, so that upon the initial opening movement of the flap, 24, the button, 34, will push the contact spring, 31, into contact with the contact spring, 32, and cause the signal to be sounded. The spring arm, 35, is designedly 20 sufficiently flexible to permit the flap, 24, to be fully opened, notwithstanding the resting of the button, 34, by its contact with the contact spring, 31, and said spring arm, 35, serves to insure the return of the flap to its closed position. To insure that a letter cannot be deposited past the flap without sounding the signal, 45 the lower margin of the slot, 8, is folded inwardly forming a lip, 8^a, over which the flap swings, and from above which it must be swung inwardly the width of the lip in 50 order to admit the thinnest letter or card; and in this distance of opening movement of the flap, the signal circuit is closed in the manner described.

The signal utilized in the above described 55 manner will most conveniently and desirably be in the usual "door-bell" of the house, and it is a matter of convenience to mount the push button for operating the door bell for its ordinary purpose on the fixture, 26,

and thereby utilize the switch and wiring 60 connections which serve the purpose of the automatic signalling of deposit of mail. For this purpose the front of the fixture, 26, is provided with a push button opening at 30, and at the inner side of the front wall of the said fixture there is fulcrumed a bell crank lever, 41, whose upstanding arm carries the button, 42, protruding at the opening 30, while its rearwardly extending arm carries the terminal boss, 43, which overhangs the upper contact spring, 31. A spring, 44, under the rearwardly-extending arm holds the push button normally protruded and the terminal, 43, only just in contact with the spring, 31, without depressing the latter; but upon intrust of the push button the contact spring, 31, is depressed into contact with the spring, 32, closing the circuit and operating the door bell.

When the house is equipped with a speaking tube, it is convenient to locate the speaking tube mouth-piece in proximity with the front wall of the fixture, 26, is provided with the speaking tube mouthpiece shown at 40. This will be omitted when not needed and the fixture will thereby take a different form shown in Figure 3.

I claim:

1. A mail receptacle having at the upper part a mail slot and having a vertically hinged horizontally and outwardly swinging door provided with an inwardly projecting ledge positioned for lodgment thereon of matter entered through the slot, the receptacle having at the side of its chamber sufficiently flexible to permit the flap, 24, to proximate to which the free edge of the door closes, an inclined guide plate for the material entered through the slot, sloping down away from that side of the chamber 10 past the proximate edge of the door opening, for preventing encounter of said matter with the edge of the door opening in the opening movement of the door.
2. The combination with a mail receptacle having a vertically hinged horizontally swinging door, means carried by the door extending into the receptacle for receiving mail dropped thereinto, of a deflecting plate carried by the wall of the receptacle adjacent one side and adjacent the free edge of the door for deflecting mail past said edge of the door onto the mail-receiving member.

In testimony whereof, I have hereunto set my hand at Chicago, Illinois, this 14th day of March, 1922.

HERBERT C. COY.
